UNITED STATES PATENT OFFICE.

CHARLES A. PRATTE, OF DENVER, COLORADO, ASSIGNOR OF ONE-HALF TO CHARLES E. FULLER, JR., OF DENVER, COLORADO.

VACUUM SANDER.

Application filed March 20, 1928. Serial No. 263,049.

This invention relates to improvements in vacuum sanders for locomotives and has reference more particularly to an improvement in that type of sander shown and described 5 in United States Letters Patent 1,263,106, granted to me on April 16, 1918.

In the operation of railway trains it is frequently necessary to employ sand so as to prevent the slipping of the drivers of the 10 locomotives. In order to direct the sand into the space between the ball of the rail and the periphery of the driving wheels of the locomotive, the sand is usually applied by means of an air blast so as to assure its application 15 in the position desired. For the purpose of applying the sand, an air-operated suction device is employed which is connected with the sand dome on the locomotive boiler and which can be controlled by the locomotive engineer so as to produce the necessary sand blast whenever it is desired to do so. In present day locomotive practice, the locomotives are supplied with a large number 20 of drive wheels which may vary from four on each side to a much larger number. In order to properly sand the track at each wheel, it is evident that sanders of large capacity must be employed.

It is the object of this invention to produce 30 a sander of a novel construction that shall be so designed that each sander will supply two wheels and which will therefore make it possible to properly sand a large number of drive wheels from the same sand box or dome.

In order to most clearly describe my invention, reference will be had for this purpose to the accompanying drawing in which the preferred embodiment thereof has been illustrated, and in which:

Fig. 1 is a side elevation of a locomotive showing my invention applied thereto;

Fig. 2 is a section taken on line 2—2, Fig. 1; and

Fig. 3 is a section taken on line 3—3, Fig. 2.

In the drawing numeral 1 represents the ball of the railway rail and numeral 2 the drivers of the locomotive. In the example given I have shown four drivers on each side.

A sand pipe 3 terminates at a point a short distance above the surface of the rail and to the front surface of the driver in the manner shown in the drawing. The sand is usually contained in a sand box or dome 4, which is located on the top of the locomotive.

This sand box is provided with a removable

cover 5, through which the sand is introduced. Ordinarily these sand domes or boxes have a circular cross section like that shown in Fig. 2 in which numeral 6 represents the cylindrical side wall. For the purpose of 60 transferring sand from the interior of the sand dome to pipes 3, I have provided a mechanism which has been illustrated in section in Fig. 3, and which consists of a pipe 7 having a short portion 8 that extends at 65 right angles to the main part of the pipe and terminates in an internally threaded opening 9. The end of section 7 also terminates in an internally threaded opening 10. A sleeve 11 has a threaded engagement at one end with the threads of opening 10 and extends through a hole 12 in the cylindrical wall 6. Secured to the outer end of the threaded connector 11 is an L 13. When this L is in place 70 it serves as a clamping means for securing 75 pipe 7 in place in the opening 12. A sand pipe 3 is connected to the downwardly extending opening of L 13 in the manner shown in Fig. 3. This L has an opening 14 which is in axial alignment with the opening to 80 which pipe 3 is connected and located within opening 14 is a nozzle 15. This nozzle is connected by means of pipes 16 to a valve 16^a that is located in the cab and which controls 85 the flow of air through the pipes 16. Secured to the threads in opening 9 is a threaded sleeve 17 which corresponds to sleeve 11 above referred to. An inverted bell shaped member 18 has its base provided with an opening 19 for the reception of the sleeve 17. 90 This bell is of such size that when its upper surface is in contact with the lower end of part 8, the lugs 20 that extend downwardly from its lower end will rest upon the bottom 21. The sides of this bell shaped member are 95 provided with a plurality of longitudinal slots 22. A suction head 23 is threadedly connected with the sleeve 17 and serves to hold the inverted bell shaped member 18 in place. The lower end of suction head 23 which has 100 been indicated by numeral 24, terminates a short distance above the bottom member 21. When dry sand is put into place in the sand dome, part of this sand will flow through the openings 25 into the interior of the inverted bell 18 and sand will also flow through the slots 22. The action of the bell shaped member 18 is to prevent the sand from packing about the suction nozzle and to therefore 105 leave it in a loose condition so that it will be 110

more readily entrained by the air when the device is operated.

From Fig. 2 it will be seen that the part indicated by numeral 8 in Fig. 3 has two branches, each of which has been designated by the numeral 7 and therefore a single suction nozzle serves for two branches and for two sand pipes. The nozzles 15 located within each of the L's 13 are connected in parallel by means of a pipe 16 in the manner shown in Fig. 2. When the engineer opens the valve 16^a and permits air under pressure to flow through pipe 16, this will produce a stream of air of high velocity at the end of each nozzle 15. It is well known that when air issues from a nozzle and is directed into an opening that a partial vacuum is produced. This vacuum causes air to flow inwardly through the suction nozzle 23 and upwardly 10 through pipe 8, and thence through the branch 7. This stream of air carries with it sand and this sand is then directed downwardly through pipes 3 and is delivered onto the surface of the railway rail directly in front of the drivers. It is evident that with the construction shown, it is possible to sand a pair of drivers with each device employed and when four sanding devices are used, eight drivers can be taken care of. It is obvious 20 that as a larger number of drivers are to be sanded, that additional sanding devices can be employed, but as this merely is a matter of duplication, the arrangement shown in this drawing and described above is considered sufficient for the purpose of describing the operation of the device.

I want to call particular attention to the function performed by the inverted bell shaped member 18 which serves both as a support for the inner end of the tubular member comprising parts 7 and 8, and as a means for preventing the packing of the sand about the suction nozzle, during such times as the device is in operation. Member 18 also serves 40 to make the flow of sand more uniform than it would be if a large body of sand would be in direct contact with the suction nozzle.

The idea of employing a single suction nozzle for two sand pipes simplifies the arrangement and decreases the cost of construction and also makes it possible to make provision for a larger number of sand pipes from each sand dome.

The pipes by means of which the compressed air is delivered to the nozzles 15, have all been designated by numeral 16, as they are all a part of a single air conduit and this designation simplifies the description.

From the above it will be apparent that I have produced a simple vacuum sanding device which is especially well adapted for use on locomotives having a large number of driving wheels and which is of simple and substantial construction and which, in addition, is provided with means that prevents the

sand from packing and thereby produces a more uniform operation than the device shown and described in the patent above identified.

Having described the invention what is claimed as new is:

1. A sander for locomotives comprising a branched conduit adapted to extend through the wall of a sand box, the inner ends of said branches terminating in a downwardly extending portion whose lower end forms a suction nozzle, a bell shaped member enclosing the suction nozzle, said member having spaced lugs adapted to rest upon the bottom of a sand box, each of said branches having their outer ends closed and an air nozzle mounted on the outer extremity of each branch and arranged to discharge air across the axis thereof. 75

2. A sander for locomotives comprising, a branched conduit, one end of said branches terminating in a single tubular portion extending at right angles to the plane of the branches, a suction nozzle secured to the end of the tubular portion, a bell shaped guard member secured to the tubular portion and enclosing the suction nozzle, said guard member having its open end provided with spaced lugs adapted to rest on the bottom of a sand box, and means applied to the outer end of each branch for producing a suction. 80

3. A sander for locomotives comprising a tubular member having one end open and the other closed, a conduit in communication with the interior of the tubular member near its closed end, said conduit extending substantially at right angles to the axis of the tubular member, a suction producing means attached to the outer end of the conduit, a suction nozzle secured to the open end of the tubular member, and a guard member enclosing the suction nozzle, said guard member having a plurality of openings for the entrance of sand. 95

4. A sander for locomotives comprising a tubular member having one end open and the other closed, a plurality of conduits, each having one end in communication with the interior of the tubular member near its closed end, said conduits extending substantially at right angles to the axis of the tubular member, a suction producing means attached to the outer end of each conduit, a suction nozzle secured to the lower end of the tubular member, a bell shaped guard member secured to the tubular member and extending downwardly over the suction nozzle, and spaced lugs projecting downwardly from the open end of the guard member. 110

5. A sander comprising a hollow body member consisting of a short tubular member having one end closed and the other open, a plurality of angularly related conduits extending radially from the tubular member near its closed end, the interiors of said con- 115

duits being in communication with the interior of the tubular member, the outer ends of each conduit being interiorly threaded, and the open end of the tubular member being interiorly threaded, a threaded sleeve in each conduit and in the threaded opening in the tubular member, a suction producing device threadedly connected with the threaded sleeve at the outer end of each conduit, a

suction nozzle threadedly connected with the threaded sleeve in the end of the tubular member and a bell shaped guard member clamped between the tubular member and the suction nozzle, said guard member being provided with spaced openings for the admission of sand.

In testimony whereof I affix my signature.
CHARLES A. PRATTE.
